REED FOR WIND MUSICAL INSTRUMENTS

Filed July 30, 1924

FIG. 1

FIG. 2

INVENTOR
Paul Arthur
By Visser & Crane
ATTYS.

UNITED STATES PATENT OFFICE

PAUL ARTHUR, OF ELKHORN, WISCONSIN, ASSIGNOR TO FRANK HOLTON & CO., OF ELKHORN, WISCONSIN, A CORPORATION OF ILLINOIS

REED FOR WIND MUSICAL INSTRUMENTS

Application filed July 30, 1924. Serial No. 729,027.

This invention relates to reeds for wind instruments, such as saxophones, clarinets, bassoons, oboes, musettes, and others of the type employing a reed to produce vibration.

5 The object of the invention is to provide reeds which shall be of more uniform character than heretofore produced, which shall be impervious to moisture, which shall have long life, which shall produce uniform tone effects throughout the period of their life, and which shall be of improved construction and operation.

10 The invention is exemplified in the combination and arrangement of parts shown in the accompanying drawing and described in the following specification, and it is more particularly pointed out in the appended claims.

In the drawing—

15 Fig. 1 is a perspective view of a reed embodying the present invention; and

20 Fig. 2 is a longitudinal section of a saxophone mouth piece showing the reed in place thereon.

The reed 10, as illustrated in Fig. 1, has 25 a flat under face 11 and a rounded upper face 12 at one end. The upper face is gradually reduced and flattened to produce a thin vibrating tongue 13 at the opposite end. Because of the nature of the material used the reed 30 may be readily made in any desired shape and thickness and the characteristics of the reed may be kept uniform for any number manufactured.

In Fig. 2 the numeral 14 designates a saxophone mouthpiece having the reed 10 secured thereto by a band 15 and clamping screws 16.

35 Heretofore reeds have commonly been made of bamboo by cutting the same into proper shape. It will be readily apparent that this 40 material and method of manufacture does not lend itself to uniformity of product and requires more or less skill in its manufacture. Moreover, the material is such that it absorbs moisture and so loses its efficiency.

45 The present invention contemplates the manufacture of reeds from a phenolic compound. It has been found that phenolic compounds when shaped to form a reed will produce the desired vibration and will give uniform improved tone qualities. The material

may be worked by any of the usual processes for handling material of this nature. By employing a molding operation for producing the reeds, the reeds may be produced in any numbers, all of the reeds being of the same 55 uniform quality. Because the material is one which can be molded it will be apparent that there is practically no limit to the shapes and proportions in which the reeds may be manufactured. This, of course, is not true of bamboo reeds where the grain and thickness of material available limits the size, shape, and proportion of the reeds. Since the phenolic material is not absorptive of moisture it will 60 maintain its uniform quality for an indefinite 65 period. It has been found that in some cases it may be desirable to add to the material before molded, fibrous substances, such as silk or wood fibers, to decrease the brittleness of the finished product. It will be apparent that any 70 thread-like material may be used for this purpose.

Another advantage of the phenolic compound for the manufacture of reeds is that suitable coloring matter may be added or the 75 material treated in any suitable manner to produce any desired color. Heretofore it has been necessary to permit the reed to retain its nature color since painting or otherwise coloring bamboo is impractical because the reed 80 must be taken into the mouth of the player. In the manufacture of the reed the phenolic compound while soft may have suitable fibrous material and coloring matter mixed therewith, after which the material may be 85 molded into proper shape and permitted to harden.

I claim:—

1. A reed for wind musical instruments constructed entirely of a phenolic compound 90 moulded to form a relatively thick body portion and a thin vibratory tongue at one end.

2. A reed for wind musical instruments comprising a phenolic compound having a relatively small amount of fibrous material 95 incorporated therein.

3. A reed for wind musical instruments comprising a phenolic compound having a relatively small amount of fibrous material incorporated therein and moulded into a body 100

portion having a relatively thin tongue at one end thereof.

4. A reed for wind musical instruments comprising a phenolic compound having fibrous material and coloring matter incorporated therein and moulded into a body portion having a vibratory tongue at one end thereof.

5. A reed for wind musical instruments constructed entirely of a phenolic compound moulded to the desired form.

In testimony whereof I have signed my name to this specification on this 18th day of July, A. D. 1924.

PAUL ARTHUR.
